UNITED STATES PATENT OFFICE.

CHARLES H. METZ, OF WALTHAM, MASSACHUSETTS.

DESIGN FOR A PEDAL FOOT-PLATE.

SPECIFICATION forming part of Design No. 25,441, dated April 28, 1896.

Application filed April 24, 1895. Serial No. 547,046. Term of patent 7 years.

To all whom it may concern:

Be it known that I, CHARLES H. METZ, of Waltham, in the county of Middlesex and State of Massachusetts, have invented and produced a new and original Design for Pedal Foot-Plates, of which the following is a specification, reference being had to the accompanying drawings, forming part thereof.

Figure 1 represents a view of a foot-plate for pedals, illustrating my design. Fig. 2 represents a view of such a plate, illustrating modifications thereof.

The leading feature of the design consists in the general outline of the plate.

In the drawings, 5 represents the main portion of the foot-plate. At the lower portion this plate is contracted to 6 6, from which portions the ends curve gradually outward and upward to 7 7, thence downward in con-

cave curves to 8 8, the ornamentation of the main body of the plate, as well as the outline between the portions 6 6 and 8 8, being immaterial.

In the modification shown in Fig. 2 the outline of the plate includes upper horns 9 9 and lower horns 10 10. From the tips of the horns the outlines extend in concave curves 11 and 12 to the points 13 13 and 14 14, while the ends of the plate are finished by the curves 15 15 and 16 16, meeting at the points 17 17.

What I claim is—

The design for a pedal foot-plate as herein shown and described.

CHARLES H. METZ.
